UNITED STATES PATENT OFFICE.

JOHN H. THOMAS, OF DENVER, COLORADO, ASSIGNOR OF ONE-HALF TO LOUIS T. ROBERTS, OF DENVER, COLORADO.

AEROPLANE.

Application filed June 17, 1929. Serial No. 371,395.

This invention relates to improvements in the construction of aeroplanes and airships of the heavier than air type.

In the operation of airships especially 5 those of the usual type which are provided with wings and which employs a tractor propeller difficulty is sometimes experienced in rising from the ground, especially when the plane is heavily loaded, and in landing it is 10 necessary to have a clear landing place of a considerable area owing to the fact that the great amount of momentum possessed by the plane will carry it along for a long distance after it has touched the surface of the ground.

15 In the operation of aeroplanes, it is sometimes very desirable and necessary to be able to rise quickly to higher elevations and this is particularly true when planes are employed on scout duty during war as it often 20 happens that this is the only means by which the aviator can save himself and his ship.

It is the object of this invention to produce an airship which shall be provided 25 with auxiliary propellers that are located in the center of the fuselage directly above the center of mass of the airship and which can be rotated about the transverse horizontal axis with respect to which the propeller shafts are perpendicular so that the 30 operator may incline the propellers forwardly or rearwardly with respect to the horizontal plane of symmetry of the aeroplane and which therefore can be employed to produce a lifting force when starting and which 35 can also be used for retarding the velocity of the ship in landing as well as for producing a force tending to raise the ship vertically.

In order to more clearly describe this 40 invention and its operation reference will now be had to the accompanying drawings in which the preferred embodiment thereof has been illustrated, and in which:

Fig. 1 is a top plan view of my improved 45 aeroplane, portions being shown in section;

Fig. 2 is a side elevation of the plane with the central part thereof shown in section;

Fig. 3 is a section taken on line 3-3,

Fig. 2;

Fig. 4 is a section taken on line 4-4,

Fig. 3; and

Fig. 5 is a section taken on line 5-5,

Fig. 3.

In the drawing reference numeral 1 represents the fuselage or body portion of the ship, and 2 the motor which operates the tractor propeller 3. In this embodiment only a single tractor propeller has been shown, but I want it understood that the invention which will hereinafter be described is just as applicable to airships having plurality of motors regardless of their location, and therefore the single propeller ship illustrated is to be considered as an example only. The interior of the fuselage is divided by transverse partitions 4 into compartments for the accommodation of freight or passenger. The ship has been illustrated as provided with two laterally extending wings 5 and horizontal and vertical rudders 6 and 7, all as is now common.

The present invention contemplates providing the fuselage with an elongated opening 8 which extends entirely through the fuselage from the top to the bottom of the latter. 75 This opening may have parallel side walls and the end walls may be formed by two angularly related walls 9 and 10 in the manner shown. Located within the opening 9 are two propellers 11 that are secured to the upper ends of propeller shafts 12. Extending transversely of the opening 8 are two I-beams 13, to the upper flanges of which are secured bearings 14. These bearings are each provided with two spaced brackets whose upper ends have openings for the reception of the transverse shaft 15. These bearings are firmly secured to the I-beams by means of bolts 16. One end of shaft 15 is provided with a double bevel gear 17. Secured to shaft 15 80 is a U-shaped member 18 having parallel downwardly extending arms 19 whose lower ends are provided with bearings 20 through which the shaft 15 extends and in which it may rotate. The connecting portion 21 of member 18 has an elongated bearing 22 85 through which the propeller shaft 12 extends. The lower end of the propeller shaft is provided with a bevel gear 23 that meshes with one of the sets of gear teeth on gear 17. A collar 24 holds shaft 12 against downward movement. Shaft 15 is held against endwise movement by means of collars 25. A drive shaft 26 is mounted for rotation in bearings 27 that are also secured to the angle irons 100 13. Shaft 26 is provided with bevel gears 28

that cooperate with one set of gear teeth on the double bevel gear 17. It is evident that when driveshaft 26 is rotated, it will cause the shaft 12 and its attached propeller 11 to be rotated. Driveshaft 26 is directly connected to a motor 29 which may be of the ordinary type employed in connection with aeroplanes, but which may be smaller or larger than the one employed for driving the 10 tractor propellers.

Since the propeller shafts 12 are mounted for rotation about their own axes, and also about the axes of shafts 15, it is, of course, necessary to provide some means for adjusting the angular position of the propeller shafts with respect to a vertical transverse flange, and for this purpose I have provided the following mechanism. A rod 30 extends between the two vertical bearings 22 and has 15 its ends provided with openings through which the bolts 31 extend. The distance between the openings in the bar 30 is equal to the distance between the axes of shafts 15 so that when this bar is in place, the propeller shafts 12 will be parallel, one with the other. Another bar 32 has one end pivotally connected with the bolt 31 that is secured to the vertical bearing 22 and the other end connected with a handle 33. This handle 20 is pivoted at 34 and is provided with the ordinary pawl which cooperates with notches in a quadrant 35. This pawl can be controlled by means of a lever 36 secured to the upper end of the handle. The control handle 33 25 has merely been shown as illustrative of means and can be replaced by any equivalent device for moving bars 32 and 30. A partition 37 has its lower end pivoted at 38 and is also pivotally connected with the bar 30 so 30 that it will move parallel with the shafts 12 at all times. The partition 37 serves to separate the opening 8 into two compartments so that each propeller will be located in a separate portion of the opening.

45 The aeroplane is, of course, provided with the usual wheels 39 and the ordinary support 40 for the rear end of the fuselage.

The engine 29 is, of course, provided with the ordinary control devices so that it may be stopped or started at the will of the operator and so that its speed may be varied to suit the conditions, all in the same manner in which the tractor propeller 3 is controlled.

Let us now assume that the parts have been 55 arranged in the manner described and that they occupy the position shown in Fig. 2. When the plane is to be started, the tractor propeller is, of course, put into rotation in the usual manner, as well as the elevating propellers 11. By speeding up the propellers the tractor propeller will pull the airship forwardly in the usual manner and since the elevating propellers are upwardly and forwardly inclined, the force produced by them will be 60 in such a direction that it can be resolved into

two components, one of which is vertical and the other of which is in the direction of movement, and therefore, they will assist in lifting the ship and also in giving a forward motion. The elevator propellers will therefore assist 70 greatly in getting the ship from the ground and will also add considerable to the action of the tractor propeller.

The elevating propellers are also of great value in landing. When the aeroplane is to 75 be landed the operator rotates the elevating propeller about the transverse axis until it is rearwardly and upwardly inclined and it will then serve as a brake and will assist in bringing the ship to a quicker stop than if this 80 propeller were not present, this makes it possible to land and to bring the ship to a stop on a much smaller field than would otherwise be necessary.

When the ship is in flight and when it is 85 desired to climb, the elevating propellers may be upwardly and forwardly inclined in the manner shown in Fig. 2 in which case they greatly facilitate the climbing and thus enables the ship to reach the given elevation in 90 a much shorter time.

If the airship is to be employed for dropping bombs during war, the elevating propellers make it possible to slow down the speed of the ship very greatly and thereby makes it 95 easier to hit a given target than it would be if the ship was travelling at maximum speed.

The advantages pointed out above are some of the most important, but there are unquestionably many others that will become apparent during the operation of a ship constructed 100 in the manner above described.

Having described the invention what is claimed as new is:

1. An aeroplane comprising, in combination, a fuselage provided with lateral wings and a tractor propeller, said fuselage having an opening extending from top to the bottom thereof, a propeller shaft in the opening, said shaft having its lower end connected with 105 a bearing rotatable about an axis transverse to the fuselage, means for rotating said shaft about its own axis, means for rotating the shaft about the transverse axis and an elevating propeller secured to the upper end of 110 the propeller shaft and located within the opening.

2. An aeroplane comprising, in combination, a fuselage having lateral wings and a tractor propeller located at its front end, the 115 fuselage having also an elongated opening extending entirely through it from top to bottom thereof, two spaced elevating propellers located in the opening, each of the last named propellers having a shaft whose lower end is 120 connected with a bearing that is rotatable about an axis that extends transversely of the fuselage and with respect to which it is 125 perpendicular, means for rotating the elevating propellers about their axes, and means 130

for simultaneously adjusting the propeller shafts about the horizontal axes.

3. An aeroplane comprising, in combination, a fuselage having lateral wings and a 5 tractor propeller located at its front end, the fuselage having also an elongated opening extending entirely through it from top to bottom, thereof, two spaced elevating propellers located in the opening, each of the last named 10 propellers having a shaft whose lower end is connected with a bearing that is rotatable about an axis that extends transversely of the fuselage and with respect to which it is perpendicular, means for rotating the elevator 15 propellers about their axes, means for simultaneously adjusting the propeller shafts about the horizontal axes, a pivoted partition separating the propellers, and means for maintaining the partition in parallel relation 20 with the propeller shafts.

4. An aeroplane comprising, in combination, a fuselage provided with lateral wings and a tractor propeller, the fuselage having an elongated opening extending therethrough from top to bottom thereof, a plurality of 25 shafts extending across the opening in a direction transverse to the fuselage, a bearing secured to each shaft, a propeller shaft having one end rotatably connected with each bearing, the propeller shafts being perpendicular to the transverse shafts, means for interconnecting the propeller shafts so that they will remain parallel while moving about the axes of the transverse shaft, means for moving the propeller shafts about the axes of the 30 transverse shafts and means for rotating the propeller shafts.

In testimony whereof I affix my signature.

JOHN H. THOMAS.
